(57) **CLAIM**

The ornamental design for an adaptor for a fuel cartridge, as shown and described.

DESCRIPTION

FIG. 1 illustrates a top front perspective view of an adaptor for a fuel cartridge in accordance with the present invention. FIG. 2 illustrates a front view of the adaptor of FIG. 1; FIG. 3 illustrates a back view of the adaptor of FIG. 1; FIG. 4 illustrates a right side view the adaptor of FIG. 1; FIG. 5 illustrates a left side view of the adaptor of FIG. 1; FIG. 6 illustrates a top view of the adaptor of FIG. 1; FIG. 7 illustrates a bottom view of the adaptor of FIG. 1; and,

FIG. 8 illustrates a left cross-sectional view of the adaptor of FIG. 1 taken along the lines 8-8 of FIG. 2, wherein the solid lines of the right cross-sectional view of the adaptor are a mirror image of the solid lines of the left cross-sectional view.

The broken lines are included for the purpose of illustrating unclaimed portions of the adaptor and form no part of the claimed design.

1 Claim, 8 Drawing Sheets
